CARTON-FEEDING MACHINE.

Application filed October 12, 1925. Serial No. 61,955.

Our invention relates to a carton feeding machine, and has for an object to provide such a machine which will feed the top carton or blank from a stack of cartons or blanks and will successively elevate the remaining cartons into position.

Another object is to provide means for adjusting the elevating mechanism so as to elevate the carrying means with the cartons thereon to a minute fraction of an inch and to the exact thickness of the carton.

A further object is to provide suction mechanism with blowing means for lifting the top carton or blank away from the stack of cartons or blanks.

Another object is to provide supporting and guiding means for supporting said top carton after it is lifted, and for discharging it from the machine.

Another object is to provide a frame comprising a plurality of sections or carriers for carrying separate stacks of cartons or blanks, one of which sections or carriers will be operated in discharging blanks, while the other sections or carriers are at rest and filled or in position to be filled during the operation of the machine.

A further object is to provide means for rotating the frame to bring one section or carrier at a time in exact position for discharging cartons and to positively hold the frame and sections in position during the discharging of said cartons.

And another object is to provide means for automatically releasing the frame and for swinging the same when the last carton is removed from the discharging section or carrier.

Other objects will appear hereinafter.

The invention consists in the combinations and arrangements of parts hereinafter described and claimed.

The invention will be best understood by reference to the accompanying drawings forming a part of this specification, and in which,

Fig. 1 is an end elevational view of our invention,

Fig. 2 is a side elevational view of the upper half of the invention,

Fig. 3 is a side elevational view of the lower half of the invention,

Fig. 4 is a plan view of the parts shown in Fig. 2,

Fig. 5 is a horizontal sectional view taken on line 5—5 of Fig. 2, showing the parts illustrated in said Fig. 2,

Fig. 6 is a horizontal sectional view, slightly reduced, taken on line 6—6 of Fig. 3,

Fig. 7 is a horizontal sectional view taken on line 7—7 of Fig. 3,

Fig. 8 is a vertical cross-sectional view taken on line 8—8 of Fig. 3,

Figs. 9 and 10 are enlarged vertical cross-sectional views taken respectively on lines 9—9 and 10—10 of Fig. 7,

Fig. 11 is an enlarged elevational detail view taken on line 11—11 of Fig. 7,

Fig. 12 is an enlarged vertical cross-sectional view taken on line 12—12 of Fig. 2,

Fig. 13 is an enlarged longitudinal vertical sectional view taken on line 13—13 of Fig. 5,

Fig. 14 is an enlarged vertical cross-sectional view taken on line 14—14 of Fig. 5, showing the carton supporting and discharging mechanism,

Fig. 15 is an enlarged fragmentary horizontal section of the mechanism shown in Fig. 14,

Fig. 16 is an elevational view of the mechanism shown in Fig. 15,

Fig. 17 is an enlarged plan view of the clutch, as seen on line 17—17 of Fig. 1,

Fig. 18 is a side elevational view, on a smaller scale of the clutch mechanism shown in Fig. 17,

Figs. 19, 20 and 21 are vertical sectional views thereof, taken respectively on lines 19—19, 20—20, and 21—21 of Fig. 18,

Fig. 22 is a horizontal sectional view taken on line 22—22 of Fig. 13; and

Fig. 23 is an enlarged side view of the cam means for operating the suction device.

The form of construction illustrated in the drawings comprises a base member or supporting member 30 from the forward part of which extend a pair of uprights 31 and 32, and from the outwardly extending side portions of which extend a pair of uprights 33 and 34 which are bent inwardly at their upper parts, as best shown in Figs. 1, 5 and 6. The upper parts of uprights 31 and 33 are connected by means of an upper supporting member 35, and the upper ends of the uprights 32 and 34 are connected by an upper supporting

member 36. Cross bars 37 and 38 connect the members 35 and 36 at the front of the frame, and a cross bar 39 connects said members at the rear of the frame. Longitudinal supporting bars 40 and 41 connect cross bars 37 and 39. A bracket 42 rests on cross bar 37 and a bracket 43 rests on supporting member 36 and is provided with a bearing sleeve 44 at its upper end, and a main drive shaft 45 rotates in said bearing sleeve and in a bearing 35' at the upper part of connecting member 35, a driving sprocket 46 being fastened to said shaft and actuated by a chain 47 (see Figs. 1 and 4), which is driven by any suitable power means (not shown).

The base member or supporting member 30 is provided with a slot 30' in which rests a bearing block 48 provided with a thrust disc 49 on which rests and rotates a vertical drive shaft 50. This bearing block is adjustably mounted in said slot and frame, as by the use of bolts 51 and bolt holes 51' (see Fig. 7) or in any appropriate manner. The shaft has keyed thereto an upper frame 52 and a lower frame 53, the upper frame being provided with diagonal arms 52' each carrying a triangular frame 52'' at its outer end; while the lower frame 53 is provided with diagonal arms 53', each carrying at its outer end a triangular frame 53'', as best indicated in Figs. 6 and 8, these diagonal arms and triangular frames being connected with vertical guide bars or plates 54. Said frames 52 and 53 are further provided with cross arms or bars 55 at the top, and with cross arms 56 at the bottom respectively. A threaded shaft 57 is rotatably mounted with its smooth ends in the ends of each companion pair of upper and lower cross arms 55 and 56, each shaft being driven by a pinion 58 at its lower end and having a hinged nut mounted on the threads of said shaft, which nut comprises parts 59 and 60 swingable apart to release the threads on said shaft, and held engaged on the threads of said shaft by means of a lever 61 with a slot 61' engaging on a lug 61''. On each part 59 of the nut is fastened a casting 62 H-like in form, on which rests a supporting plate 63 upon which the stack of cartons is placed.

The means for feeding the carton blanks comprises the horizontal shaft 45 (see Fig. 1) having a bevelled gear 64 fastened thereon and driving a bevelled gear 65 on a shaft 66 rotating in upper and lower bearings 67 on upright 31. On the lower end of shaft 66 is fastened a bevelled gear 68 meshing with bevelled gear 69 on stud shaft 70 which is rotatable in upright 31, and held in position by a pair of collars 71.

The feeding means comprises adjustable eccentric means 72 (see Figs. 3, 7 and 11) provided with a T-slot 73 having a block 74

with a T-head slidable therein and held positively adjusted in position by a pair of set screws 75, threaded in caps 76 at the ends of eccentric means 72. A link 77, which is adjustable for length, is pivoted on block 74 by a stud bolt 78 and is connected by a stud bolt 79 to a crank arm 80 which is rotatably mounted on a hub 81 pinned to a horizontal shaft 82 which is journalled in a pair of bearings 83 on base 30, and held in position by collars 83' thereon. A bolt 79 on said crank arm carries a pawl 84 which engages a ratchet 85 fastened to or integral with hub 81, the crank arm 80 being held in position on hub 81 by a collar 86 which is pinned on said hub. By adjusting the screws 75 and thereby controlling block 74 in groove 73 the effect of the eccentric means and the throw of rod 77 can be varied from one tooth on ratchet 85 to any required number of teeth thereon, so as to suit the particular thickness of carton blank which is being fed by the machine, even though this carton blank is only one-thousandth of an inch.

The horizontal shaft 82 carries a bevelled gear 87 at its inner end which meshes with a bevelled gear 88 on a shaft 89 which is journalled in a pair of bearings 90 and has a bevelled gear 91 slidably mounted thereon and rotatable therewith. An operating lever 92 engages sleeve 91' on bevelled gear 91 and is fulcrumed on a stud screw 93, said lever being adapted to disengage gear 91 from gear 58. A spring 94 normally holds gear 91 engaged with bevelled gear 58 which is provided on the bottom of screw shaft 57 to rotate said shaft and elevate the carton carrying platform 63, so as to feed the cartons one at a time from the platform which is in the discharging position, or the position indicated at the right-hand side of Figs. 3 and 6.

The means for lifting the top carton away from the stack of cartons comprises a suction mechanism (see Figs. 4, 5, 12 and 13) 110 which includes a frame 95 with side bars 96 thereon slidable in guide posts 97 which extend upwardly from the longitudinal supporting bars 40 and 41. Said frame has a yoke or arched member 98 mounted thereon 115 and provided with a top lug 98' to which is pivoted a vertical link 99 (see Figs. 1, 2 and 4) which is pivoted to a rocking lever 100 fulcrumed by a pin 101 on a bracket arm 102 mounted on a bracket 103 fastened on supporting bars 40 and 41. The other end of rocking lever 100 has a slot 104 which carries a pivot pin 105 provided on a forked arm 106 (see Figs. 2 and 23) provided with forks 107 which slidably engage over the main drive shaft 45. Said arm 106 carries a cam roller 108 moving in a cam groove 109 on cam wheel 110 which is keyed to said shaft 45. Said suction mechanism with its frame 95 is thus reciprocated vertically in 130

guide bars 97. A fan housing 111 is mounted on the lower side of frame 95 (see Figs. 12 and 13), said housing having an inlet chamber 112, from the bottom of which extend a plurality of suction tubes 113 which with said frame are movable downwardly so that their lower ends extend close to the upper carton on the stack, each tube being preferably arranged so as to extend near to the corner of the top carton on the section or platform 63. A fan 114 is mounted in housing 111 and has air inlet openings 115 for passage of air from chamber 112, said air then flowing through a plurality of side pockets 116 in the fan, and into an intake 117 of pipe 118 mounted in the side of fan housing 111. The pipe is supported in a bracket 119 supported on the frame 95, and the lower end 118' of said pipe 118 slides in a chamber 120 provided in a casting 121 bolted onto members 35 and 36. The middle of this casting 121 receives the upper end 50' of vertical shaft 50 to rotate therein. A discharge tube 122 leads from chamber 120, and has a curved end 122' which extends to the edge of the several upper cartons 63' supported on platform 63.

The means provided for driving the fan comprises a motor 123 rotatable in a motor housing 124 (see Fig. 12) which is mounted on ribs 95' of frame 95. The shaft 125 of said motor carries the fan 114 pinned thereto, and said shaft is preferably supported on suitable thrust bearings 126. The movement of rocker arm 100 reciprocates the suction mechanism including the suction tubes 113 which in their lowered position substantially engage the top of the upper carton on platform 63, and at the same time the fan forces the air through pipe 118 and tube 122 discharging said air at the edges of several of the uppermost cartons 63' on the platform 63 thereby slightly raising said cartons and especially the upper one, whereupon the suction in tubes 113 will draw and firmly hold the top carton on their lower ends thereby closing said ends and creating a suction in the tubes in consequence whereof the air no longer passes out of discharge tube 122, and the cartons immediately beneath the upper one, which have been slightly raised by the air from discharge tube 122, will thereupon settle back onto the stack of cartons. The tubes 113 are arranged to extend with their lower ends substantially to the corners of the carton, and are arranged or bent so as to suit the size of carton operated upon with the machine.

Means is provided for supporting the upper carton as soon as the same is held, by said tubes 113, slightly elevated above the remaining cartons, and this means comprises a lower side plate 127 at each side of the carton which moves beneath the side edges thereof (see Figs. 14 and 15), and an upper

plate 128 which engages above the carton at each side thereof and which is adjustably mounted on the plate 127 by means of bracket arms 129 having slots 129' through which extend pins 130 fastened on plate 127. 70 The plates 127 have T-arms 131 thereon which are slidable in T-grooves 132 on horizontal guide arms 133 extending from brackets 134 fastened with an arm 134' on frame 38 (see Figs. 5 and 13-16), and with an arm 134" onto frame members 35 and 36. The plates 127 and 128 at each side of the machine are operated by an angular lever 135 (see Figs. 15 and 16) having a forked end 136 which engages a stud screw 137 on plate 127. Said lever 135 has an upwardly extending hub 135' (see Fig. 16) which is pinned to shaft 138 fulcrumed in the ends of lugs 139 extending from arms 134" (see Figs. 5, 15 and 16). The upper end of hub 135' has a projecting arm 140 thereon with a stud 141 carrying a roller 142 which runs in a peripheral cam groove 143 provided on a cam roller 144 fastened to a shaft 145 which is journalled in the frame members 35 and 36 (see Fig. 5), there being a lever 135 with plates 127 and 128 provided at each side of the frame for receiving the sides of the carton. Said shaft 145 has a bevelled pinion 146 thereon which meshes with a pinion 147 95 on a shaft 148 journalled in boxes 149 mounted on frame member 35 (see Figs. 2 and 5), said shaft 148 carrying a bevelled gear 150 meshing with a bevelled gear 151 on the vertical shaft 66 (see Figs. 1 and 5). The movement of shaft 145 with cam roller 144 thereon oscillates lever 135 and thereby moves plates 127 and 128 out of the way of the upper carton when the same is being elevated by the suction mechanism, and moves said plates in engagement with said upper carton to hold and guide the same during the discharge thereof, when the suction mechanism is being elevated and removed from said upper carton. These plates 127 and 128 with the levers 135 and associated mechanism are made and arranged to be adjustable so that they will be adapted to fit various widths of cartons to be operated on and fed by the machine.

Means is provided for carrying away the upper carton when it is supported by plates 127 and 128, and this means comprises a shoe 152 (see Figs. 1 and 13) provided on one of the links of a discharge chain 153 travelling over an idler sprocket 154 which is rotatably mounted on shaft 145, and said chain is driven by a sprocket 155 pinned to a shaft 156 journalled in the lower part of bearings 157 mounted on upright members 31 and 32. The shaft 156 carries a pinion 158 operating a gear 159 on a stud shaft 160 journalled in the upper part of bearings 157 (see Figs. 1, 2 and 5). Shaft 160 also carries a pinion 161 meshing with a gear 162 mounted on

a stud shaft 163 journalled in frame member 35 and carrying a bevelled gear 164 which meshes with the bevelled gear 165 fastened on vertical drive shaft 66. Said gears 165 to 158 step up or increase the speed of shaft 156 four times to the speed of vertical drive shaft 66, in order to provide a complete revolution or the proper length of travel to the chain 153 with its shoe 152 for discharging the top carton from the machine onto the track means 166 or any similar suitable means for receiving the discharged carton.

The main frame construction comprises 15 four similar sections (see Figs. 6 and 8) including four supporting plates or platforms 63, each for supporting a stack of cartons thereon, as explained heretofore, and means for swinging this frame, when one stack of 20 cartons has been fed, so as to bring the next stack of cartons and platform into feeding position. As shown in the drawings the present construction comprises four sections with supporting platforms 63, and the frame 25 is swung one-fourth turn when the platform which is in feeding position, has been emptied and moved to its elevated position. The construction for rotating the frame comprises the main shaft 50 (see Figs. 3 and 8) 30 which has a cam member 167 keyed to its lower end and provided with cam teeth on the upper surface which engage cam teeth on the lower surface of a gear 168 mounted to rotate with and to slide on said main shaft 50. The gear 168 meshes with and is actuated by a rack bar 169 which has a plate 170 fastened thereunder and being slidably supported on frame 30, said plate being held in position by guide shoes 171. A link 40 172 (see Figs. 1, 6 and 7) is pivoted to said plate 170 and is driven by a crank arm 173 of a bell crank fastened on a shaft 174 journalled in a bearing 175 mounted on vertical post 32, said shaft 174 being driven by 45 a sprocket 176 and a chain 177 operating thereon and driven by a sprocket 178 fastened on the outer flange 179' of a bushing 179 which is loosely mounted on the main drive shaft 45 at the upper part of the machine (see Figs. 1 and 18).

The means provided for rotating the main frame with the carton platforms, includes a lug 180 on plate 170 fastened on rack bar 169 (see Fig. 7), said lug engaging a roller 181 at the end of lever 92 and operates said lever during the movement of the crank arm 173, to disconnect the bevelled gear 91 from gear 58, immediately before the swinging or rotating of the frame, and holds said gears 55 disconnected during the quarter turn thereof. The rear part of rack 169 operates a gear 182 (see Figs. 3 and 7) mounted on a shaft 183 journalled with its lower end in base 30 and with its upper end in a bearing bracket 184 extending up from the base. 60

Said shaft 183 has fixed thereto a disc 185 with a raised portion or cam 186 which operates a roller 187 on one end of a lever 188 fulcrumed in a bracket 189 mounted on base 30. The other end of said lever moves in a slot 190 provided in a vertical post 191 (see Figs. 7 and 9) which is slidable in a block 192 mounted on base member 30. The upper end of said post carries a brake shoe 193 having its ends slidably engaging on vertical posts 194 fastened with their lower ends in base 30. Springs 195 normally hold the shoe in its upper or operative position and hold its ends 193' between the side bars of triangular members 53'' at the rear part of 80 the machine, or at the left-hand end as seen in Fig. 6.

The rearward movement of rack bar 169, or its movement to the left-hand side as seen in Fig. 7, turns the cams on the lower end 85 of gear 168 (see Figs. 3 and 8) idly over the cams on the upper face of member 167 and does not turn the vertical shaft 50 or the frame, but upon the forward movement of said rack bar, or the movement toward the 90 right as indicated by arrow "a" in Fig. 7, the cams on the lower face of gear 168 clutches and operates the cams on member 167 and therewith rotates the attached main supporting shaft 50 and the frame sections 95 and platforms 63 supported thereon, for one quarter revolution in clock-wise direction, thus bringing the next platform into discharging position toward the forward part of the machine, or the right-hand part as 100 seen in Figs. 3 and 7; during which time gear 182 has moved lever 188 (see Figs. 3 and 7) by means of the lug 186 on disc 185, and thereby has withdrawn the brake shoe 193 from its holding or locking position between the triangular frame members 53''; and at the same time the lug 180 on plate 170 or rack bar 169 has actuated lever 92 and has thereby withdrawn bevelled gear 91 from gear 58, thus freely permitting the 105 turning of the frame with the carton supporting platforms.

The means for automatically actuating the above frame turning mechanism comprises lugs 196 (see Figs. 1, 6, 8 and 13) at the 110 sides of plates or platforms 63, and these lugs, when the platforms are in their extreme upper position engage and operate a roller 197 mounted in the lower end of a bent rod 198 which is made adjustable by 115 means of a screw-sleeve 199 and which has its upper end attached to a lever 200 (see especially Figs. 1 and 18) fulcrumed on a pivot stud 201 provided on bracket member 42. Each triangular frame 53' is notched 120 at the upper corner edges 197' to permit the roller 197 to pass freely above the same during the rotation of the frame and carton supporting mechanism. By elevating the rod 198 the lever 200 is swung so as to re- 125 130

lease the nose 202 at its end from its locking engagement with a lug 203 provided on a plunger 204 (see Figs. 17 and 18) which is slidably mounted in bushings 205 on the 5 side of vertical bracket member 42. Said plunger 204 is operated by a lever arm 206 pivoted thereto and fastened to a shaft 207 which rocks in a bushing 208 extending from the end of member 42. An upper rock arm 10 209 is fastened on shaft 207 and is provided with forks 210 pivoted to plunger 211 which is slidable in a hub 212 on top of member 42, and a spring 213 bears between said hub and a collar 214 which is adjustably mounted 15 on the end of plunger 211. The upper end of arm 209 is pivoted to a link 215 which is connected to the upper end of a clutch member 216, said member being pivoted at its lower end with a stud screw 217 on 20 bracket 42 (see Figs. 18 and 20). Said clutch member includes the main semi-circular part 216 and a companion semi-circular part 216', which parts each carry a stud 218 riding in a peripheral groove 219 provided on a clutch collar 220 which rotates in said parts 216 and 216' and is slidable therewith on shaft 45 but is made to rotate with said shaft by means of splines 221 (see Fig. 20). Collar 220 carries two studs 222 30 (see Figs. 17, 18 and 19) which are movable into pockets 223 provided in a disc 224 and in a flange 225 fastened to said disc and to sleeve 179. A roller 226 is mounted on disc 224 and during a complete rotation 35 of said disc rides over cam 227 which extends from part 216' and swings said parts 216 and 216' and thereby withdraws studs 222 out of pockets 223 in members 224 and 225 to stop rotation of members 224, 225, 179 40 and 178 (see Fig. 18). A hook member 228 is provided on member 216 and engages in a slot 229 in disc 224 when bushing 179 has made a complete turn, in order to retain said disc and the connected members at 45 rest, whereas the hub 220 which is fastened to main drive shaft 45 rotates continuously with said shaft.

The operation of the machine.—The power is applied to the main drive shaft 45 of the machine by means of drive chain 47 and sprocket 46 or any suitable positive power transmitting means, and from this drive shaft which is located at the forward upper part of the machine (Figs. 1 and 5) motion is transmitted through the connected bevelled gears to vertical shaft 66 from which it is transmitted through bevelled gears to the adjustable eccentric means 72, which is adjustable to a minute degree of 50 accuracy by means of the screw 75 and block 74 held eccentrically thereby, this mechanism being so arranged in the machine that cartons or sheets of one thousandth of an inch in thickness may be accurately fed in 55 succession. This eccentric means actuates ratchet 85 and transverse shaft 82 attached thereto (Figs. 1 and 7) which in turn actuate shaft 89 and the attached bevelled gear 91 meshing with one of the bevelled gears 58 on the bottom of one of the threaded vertical shafts 57, the rotation of such shaft moving the attached nut 60 vertically thereon and with it the section 62 and platform 63 with the stack of cartons upon said platform. During the feeding of the cartons 60 located upon the platform which is in the discharge position of the machine or at the right-hand side as viewed in Fig. 6, the main drive shaft 45 also rotates the attached cam wheel 110 and thereby the cam 80 roller 108 with the link 106 and lever 100 therewith reciprocating the pneumatic means or suction means mounted in vertical tracks 97 (Figs. 2, 12 and 13) the tubes 113 of the suction means moving downwardly 85 onto the upper carton on the stack and at the same time the air taken in through tubes 113 by fan 114 is forced through pipe 118 and through discharge tube 122 beneath the edge of the upper cartons on the stack thereby lifting the upper cartons, the top one of which will then be moved upwardly against the lower open ends of tubes 113 and held thereby; and during the upward travel of the pneumatic means with said top 90 carton the holding and guiding means, which includes the plates 127 and 128 (Figs. 5, 14 and 15) is being moved to engage above and below each side of said top carton, by means of levers 135, cam means 144, shaft 100 145 and shaft 148, with the attached bevelled gears, said shaft 148 being driven from vertical shaft 66 (Figs. 2 and 5). At the same time that the said holding and guiding means hold the top carton and permit the 105 suction tubes 113 to continue in their upward movement away from said top carton, the discharge means becomes operative and this includes the chain 153 and shoe 152 which, as shown in Fig. 13, engages the 110 rear edge of said top carton and slides it out of the holding plates 127 and 128 onto the tracks or receiving means 166 at the front of the machine. When said top carton has been discharged, then the shoe 152 moves 115 along in its upper position on the chain, and during this time the pneumatic means is again moving downwardly to bring tubes 113 into engagement with the following top carton and to lift the same by the time said shoe 152 has completed its travel and again moves downwardly over sprocket 154 into the position shown in Fig. 13. When all the cartons from the discharging platform or section have been discharged, then lug 120 125 196 on the side of said platform (Figs. 1, 13 and 18) engages roller 197 at the lower end of bent rod 198 and moves said rod upwardly, thereby actuating the tripping mechanism and releasing lever 200 so as to 130

permit spring 213 to operate lever 209 (Fig. 18) and thereby move the locking hook 228 out of engagement with disc 224 and at the same time move studs 222 into openings 223 provided in members 224 and 225, whereupon said members 224 and 225 and the attached bushing 179 rotate along with clutch collar 220 and the attached main drive shaft 45, which operation rotates sprocket 178 on bushing 179 and therewith chain 177, sprocket 176 and attached shaft 174 located at the lower front of the machine (Figs. 1, 3, 6 and 7). Shaft 174 through its crank arm 173 operates the connected rack bar 169 which rotates gear 168 loosely mounted on the main central shaft 50. During the rearward travel of said rack bar the cams on the lower face of gear 168 move freely over the cams on the upper face of member 167 which is fastened on shaft 50, but upon the forward movement of said rack bar with the crank arm 173 and intermediate links, the rack bar with gear 168 move member 167 and therewith shaft 50 one-quarter turn in clockwise direction, thus bringing the next section or platform into the discharging position on the machine. During this forward rotation of the rack bar the side lug 180 attached thereon (Figs. 3 and 7) actuates roller 181 and the attached arm 92 with bevelled gear 91 removing it from the companion bevelled gear 58 on threaded shaft 57, thus permitting free separation of said bevelled gears and the free swinging of the frame; at the same time the rear part of the rack bar has moved gear 182 with its cam lug 186 on disc 185 thereby moving lever 188 to withdraw brake shoe 193 from between the triangular frame bars 53", whereupon the frame is free to rotate one-quarter turn, and before the completion of this turning or swinging of the frame the brake shoe 193 engages beneath the triangular frame members 53" to snap in between the same into braking or holding position at the exact moment when the frame has completed its one-fourth swing or revolution, and by this time the rack bar has been moved in its rearward position to release roller 181 from lug 180 on the rack bar and thereby permit lever 92 to return so that bevelled gear 91 can move into engagement with the bevelled gear 58 on threaded shaft 57 of the succeeding section which has been moved into discharging position.

The machine has been shown provided with four sections and platforms, but a larger or smaller number may be provided, and it is apparent with this arrangement that all the sections may be filled with stacks of cartons and one section after the other may be brought into proper discharging position and the cartons successively discharged therefrom, and while the cartons from one section are being discharged, the

other sections may be again filled or replenished during the operation of the machine.

Having described our invention what we claim as new and desire to secure by Letters Patent is:

1. A carton feeding machine comprising platform means for supporting a stack of cartons; a track and means movably mounted thereon for lifting the upper one of the cartons; movable means for receiving, holding and guiding the lifted carton; and means for operating said receiving, holding and guiding means in conjunction with said lifting means. 70

2. A carton feeding machine comprising platform means for supporting a stack of cartons; pneumatic means for lifting up the top carton from the stack of cartons; a movable plate arrangement for receiving and supporting the lifted carton; and means for advancing the plate arrangement into receiving relation to the lifted carton for the support of the carton thereon. 75 80

3. A carton feeding machine comprising platform means for supporting a stack of cartons; track means and pneumatic means movably mounted thereon for lifting up the top carton from the stack of cartons; a movable plate arrangement for engaging above and below the edges of the lifted carton by which to support the same; and means for alternately moving the plate arrangement into carton receiving and carton discharging position. 90 95

4. A carton feeding machine comprising platform means for supporting a stack of cartons; pneumatic means mounted for movement toward and away from said platform and including means for lifting the upper one of the cartons; cooperating plates arranged to receive and carry the lifted carton from its lifted position; an endless chain with a shoe arrangement thereon to engage and discharge the carton from said cooperating plates; a driving shaft; and means controlled by the operation of the driving shaft for effecting the operation of said pneumatic means, cooperating plates, and endless chain. 100 105 110

5. In a carton feeding machine, means for supporting a stack of cartons, pneumatic mechanism including stationary means for blowing against the edge of the upper cartons to move them upwardly, and movable suction tubes having connection with said blowing means and arranged to contact with and lift up the upper carton from the stack, said pneumatic means being arranged to stop the discharge of air to said blowing means when the upper carton is engaged and lifted by said suction tubes. 115 120 125

6. In a carton feeding machine, means for supporting a stack of cartons, pneumatic mechanism including suction means for lifting the upper carton, blowing means ar- 130

ranged to receive air from the pneumatic mechanism for raising the upper ones of the stack of cartons, a track on which said pneumatic mechanism is movably mounted, and means for intermittently moving said pneumatic mechanism on said track.

7. In a carton feeding machine, means for supporting a stack of cartons, pneumatic means for lifting the upper carton of the stack, and means for moving said pneumatic means toward and away from said cartons, said means including a rocking member mounted between its ends and having one end operatively connected with the 15 pneumatic means, and a rotary member with eccentric means thereon operatively connected with the opposite end of said rocking member.

8. In a carton feeding machine, means for supporting a stack of cartons, pneumatic means for lifting the upper carton, track means in which said pneumatic means travels, a rocking lever having support between its ends and connected at one end to said 25 pneumatic means, and a wheel with a cam groove and a cam moving therein and connected to the opposite end of said rocking lever for reciprocating said pneumatic means in said track means.

30 9. In a carton feeding machine, means for supporting cartons, pneumatic means movably mounted in track means on said machine and including suction tubes for engaging and lifting the carton, a pipe connected to said suction tubes and movable therewith, a chamber on said machine in which said pipe telescopes, air discharge means leading from said chamber to the edge of said carton, and means for reciprocating 35 said pneumatic means.

40 10. In a carton feeding machine, means for supporting cartons, pneumatic means including a fan housing with a fan therein, suction tubes extending from said fan housing to engage the carton, a chamber on said machine, an air pipe for conducting air from said fan housing to said chamber, air discharge means extending from said chamber to the edge of the carton, and means for 45 moving said fan housing with said fan and the suction tubes toward and away from the cartons.

50 11. In a carton feeding machine, means for supporting a stack of cartons, suction means including a fan housing with a fan therein and suction tubes extending from said fan housing toward the carton, an air pipe leading from said fan housing, air discharge means connected with said air pipe 55 for discharging air to the edge of the upper cartons of the stack to lift the same, means for reciprocating said pneumatic means to intermittently move the same upwardly to inoperative position and downwardly to operative position to lift the upper carton by

means of said air discharge means and said suction tubes.

12. In a carton feeding machine, means for lifting a carton, and means for supporting the lifted carton comprising movably 70 mounted cooperating plates arranged for engagement over the opposite sides of the lifted carton.

13. In a carton feeding machine, means for lifting a carton, and movably mounted 75 cooperating feeding means arranged to engage above and below the lifted carton and adapted to act as track means for holding and guiding the carton.

14. In a carton feeding machine, means 80 for lifting a carton, and means for holding, carrying and guiding the lifted carton comprising movably mounted cooperating plates arranged to slide into engagement over opposite edges of the carton and to engage 85 above and below said edges.

15. In a carton feeding machine, means for lifting a carton, and means for holding and guiding said lifted carton, said holding means comprising a pair of plates engageable beneath each side of the carton and a pair of plates engageable above the sides of the carton, and means for alternately swinging said holding means toward and away 90 from the sides of the carton. 95

16. In a carton feeding machine, means for supporting a stack of cartons, means intermittently actuated for lifting the upper one of said cartons, plate means for holding and guiding said lifted carton, and 100 means including a pair of swinging levers and rollers with cam means thereon for swinging said levers to move said plate means in engagement with said carton to hold and guide the same when said carton 105 has been lifted, and means for operating said holding means in conjunction with said lifting means and to withdraw said lifting means from the carton retained by said holding means. 110

17. In a carton feeding machine, means including guide members for engaging above and below the edge of a carton to support the same, and means including an endless chain with a shoe arranged thereon for engaging said carton and moving the same on said guide members to discharge the carton 115 therefrom.

18. In a carton feeding machine, means for lifting a carton, holding and guiding means for engaging the sides of said carton, means for intermittently actuating said holding and guiding means toward and away from said carton, and discharge means including a shoe for engaging said carton to move the same from said holding and guiding means. 120 125

19. In a carton feeding machine, pneumatic means for lifting a carton, means for holding and guiding said carton and includ- 130

ing members engaging above and below the edges of said carton and cam means for alternately actuating said holding and guiding means, and means including a chain 5 with a shoe for engaging a carton to discharge the same from the holding means.

20. A carton feeding machine comprising means for supporting and elevating a stack of cartons, pneumatic means for lifting 10 the upper carton from said stack and including suction means for engaging said carton and air discharge means for blowing beneath the edge of said carton, holding and guiding means for engaging and guiding said lifted upper carton, and including means movable above and below the sides 15 of said cartons and means for alternately swinging the same toward and away from said carton, means including a shoe for engaging said upper carton and discharging it from said holding means, and operating mechanism for actuating said lifting means 20 to engage the upper carton when the elevating means is at rest and for moving said holding means and said discharge means into 25

operative position and thereupon withdrawing said lifting means.

21. A carton feeding machine comprising a platform for supporting a stack of cartons, pneumatic means for lifting the upper 30 carton from said stack, means for actuating said pneumatic means to engage and slightly lift said upper carton when said elevating means is at rest, means for holding and guiding said lifted carton and including 35 plate means slidably into engagement with the sides of said carton, means for advancing and retiring said holding means relatively to the carton, means for engaging and discharging the carton from the supporting and guiding means, and means for elevating said pneumatic lifting means away from the upper carton when said holding means and discharging means are operative.

In testimony whereof, we have signed 40 our names to this specification.
